Primary Examiner — Leanne Was-Englehart*(74) Attorney, Agent, or Firm* — Buchanan Ingersoll & Rooney PC(57) **CLAIM**

The ornamental design for a railing bottom rail, as shown and described.

DESCRIPTION

FIG. 1 is a perspective view of our railing bottom rail; FIG. 2 is an end view thereof; FIG. 3 is a left side view thereof, the right side being a mirror image thereof; FIG. 4 is a top view thereof; and, FIG. 5 is a bottom view thereof.

The break lines depict bounds of the Claim. The portion between the break lines forms no part of the claimed design.

1 Claim, 2 Drawing Sheets(56)
